TELEPHONE TRANSMISSION SYSTEM

Oliver B. Jacobs, Morristown, N. J., assignor to
 Bell Telephone Laboratories, Incorporated,
 New York, N. Y., a corporation of New York

Application March 25, 1930, Serial No. 438,720

5 Claims. (Cl. 179—170)

This invention relates to speech transmission systems which are electrically long and more particularly to such systems as transoceanic cable circuits including voice controlled devices.

5 An object of this invention is to inform a subscriber talking over a long circuit as to the period of time which should elapse before he should expect a reply.

Another object is to apprise the talker at the 10 terminal end of the circuit that the apparatus in the circuit is conditioned for transmitting in a particular direction.

Voice controlled terminal apparatus for electrically long telephone systems are generally arranged to transmit signals in one direction at a 15 time. The voice currents entering the terminal station at once actuate the operating means to transmit the signals to the line. The first of two subscribers to begin talking controls the circuit either by having a portion of the voice energy introduced into the controlling apparatus for connecting the circuit in the proper direction for 20 transmission or by causing a carrier current to be sent out in advance of the voice currents to prepare the way for the latter. U. S. Patents to H. A. Barton 1,574,781, issued March 2, 1926; H. D. Arnold 1,565,302 issued December 15, 1925; R. C. Mathes 1,678,188, issued July 24, 1928; and H. Nyquist 1,674,695, issued July 26, 1928, disclose 25 several such arrangements.

A difficulty experienced in such systems (for example, experimental circuits set up to simulate transoceanic cable circuits) is that a talker, awaiting a reply, does not wait sufficiently long 30 for a response, but tends to resume talking before the apparatus is conditioned for transmitting a reply from the subscriber at the distant terminal. The longer the time of transmission in such systems, the greater the difficulty becomes.

40 In accordance with the present invention it is proposed to overcome these difficulties by providing circuit means to impress an audible signal on the circuit toward the talker at one terminal during the entire time that the circuit is in the condition under which message waves from the other terminal cannot come through. This gives the talker a means for determining how long to wait for a response. The subscriber will observe that the tone ceases shortly after he stops talking and 45 that it is not present when he hears the other party talking. The subscriber soon learns that speech from the other end cannot be expected to be heard until the tone ceases and his reaction is to await the cessation of the tone before expecting an answer.

According to one feature of this invention, circuit means may be provided to prevent the tone from being heard by the talker except in the interval after he has ceased talking and until the circuit is in the condition under which message waves transmitted from the other end can come through. 5

Circuits embodying the invention will now be described in connection with the accompanying drawing: 10

Fig. 1 of which is a diagrammatic circuit of a typical repeater unit embodying this invention and

Fig. 2 of which shows a diagrammatic circuit of a system illustrating a modified form of this 15 invention.

In the arrangement of Fig. 1 there is shown a section of a transmission line "L" with a terminal two-way repeater unit. The terminal repeater is of a type well known in the art. 20

The terminal circuit comprises essentially a repeater circuit having amplifiers AE and AW connected to the line sections through hybrid coils 10 and 11, the line sections being balanced by networks N and N¹. The usual delay circuit 25 is associated with each amplifier. Bridged across the repeater path east in front of the delay circuit is an echo suppressor unit AD. A similar echo suppressor unit A¹D¹ is bridged across the path transmitting west in front of its associated 30 delay circuit. These echo suppressors are of a type well known in the art, the detailed arrangements being illustrated for example in U. S. Patent 1,560,544 issued to G. Crisson November 10, 1925 and include suitable vacuum tube amplifying and rectifying apparatus for rectifying the voice currents to operate a relay. Associated with echo suppressor AD are relays R and R¹ 35 which operate in the following manner.

When voice currents are transmitted from 40 west to east the echo suppressor AD will actuate its relays R and R¹ in response to the voice currents to short circuit the repeater path transmitting east to west so that the repeater is then only capable of transmitting from west to east, 45 and also to send an audible tone from source of oscillations of audio frequency G through the contacts of relay R back toward the talker over hybrid coil 10.

Coil 10 and network N are suitably balanced 50 so that the tone from source of oscillations G is transmitted toward the subscriber only and cannot find its way back through the amplifier AE into the line L. Relay R is designed in a manner well known in the art to be slow in releasing 55

its contacts after the energizing current has been removed from its winding. The time for the release of the relay contacts may be adjusted to the time it takes the apparatus located at all 5 stations between the subscribers to return to normal after a subscriber ceases to talk. In this manner there will be impressed toward the talker an audible tone only during the time the circuit is in condition under which speech waves transmitted from the other terminal cannot come 10 through.

Relay R¹ has an extra contact 12 which normally short circuits a source of oscillations O. When the suppressor AD is actuated in response 15 to voice currents transmitted from west to east, the contact 12 is opened and the generator O at once transmits oscillations of the frequency of the generator to the line L through high pass filter HP. The carrier frequency oscillations 20 transmitted by the generator O act as a carrier controlling current and are transmitted over line L for the purpose of conditioning the apparatus at the remote terminal (not shown) for the reception of voice currents before the voice currents, which are delayed by the delay circuit, 25 arrive. Although one manner of controlling the circuit apparatus has been described, it is to be understood that the scope of the invention includes any other means for controlling the circuit. The system for transmitting from one subscriber to another may employ reversible repeaters, one-way repeaters, or any type of repeater suitable for use in a toll or long distance circuit.

Referring to Fig. 2, a transmission line, such 35 as a submarine cable TC, is illustrated schematically as being connected to a subscriber at terminal station A through intermediate repeater B and cable terminal station C. The stations are shown connected together through line sections L' which terminate at each station. Station A comprises essentially a repeater circuit having amplifiers A'E' and A'W' connected to the line sections through hybrid coils H₁ and H₂ and the balancing networks N₁ and N₂. Intermediate repeater 40 B is shown having hybrid coils H₃ and H₄, balancing networks N₃ and N₄, an echo suppressor unit of a type well known in the art, for example as illustrated in U. S. Patent 1,560,544 issued to G. Crisson November 10, 1925. Station C 45 is the cable terminal station for the submarine cable line and comprises hybrid coil H₅, balancing network N₅, and apparatus of any type suitable for connecting a line station to a long submarine cable; namely, the usual amplifiers such 50 as one-way amplifiers A''E'' and A''W'', anti-singing echo suppressing apparatus, etc. At this station there is shown the preferred embodiment 55 of this invention which comprises amplifier rectifier AR and relay R'' which operates when voice currents are transmitted from west to east. The amplifier rectifier AR may be part of the 60 echo suppressor equipment at the cable terminal station or separate from such equipment. Relay R'' is designed as a slow release relay and is provided with normally open contacts to which a 65 source of oscillations of audio frequency G' is connected. When relay R'' operates in response to the voice currents transmitted from west to east, its contacts close and an audible tone from G' is sent back over the east to west path of 70 transmission toward the talker at station A. The tone is prevented from being sent over submarine cable TC by the usual terminal apparatus located at C. This apparatus may comprise a one-way 75 amplifier A''W''.

When voice currents are transmitted from west to east, the echo suppressor SE in repeater B will actuate its relay in response to voice currents and thus short circuit the repeater path for east to west transmission so that repeater B is then only capable of transmitting from west to east. When voice currents are transmitted from east to west suppressor SW actuates its relay to short circuit the repeater path from west to east so that the repeater will now only transmit 10 from east to west.

The usual delay circuits, which may be associated with the repeater path and which are not shown in this diagram since they form no part of this invention, delay the transmission of the 15 voice currents through a given path for an interval of time sufficient to enable the suppressor to short circuit the opposite path before the voice currents have been transmitted through the hybrid coil or before reflection currents due to unbalance may be transmitted back over the other path in the opposite direction.

When the west to east currents arrive at cable terminal station C amplifier rectifier AR, which is bridged across the west to east path of transmission, actuates relay R'' and an audible signal from source of oscillations G' is sent back over east to west path toward the talker at A. Echo suppressor SE at intermediate repeater B, which had previously operated when the west to east 30 currents had arrived at B and had short circuited the east to west path, will prevent the tone from being heard by the subscriber at station A until the short circuit is removed. When signal transmission from west to east ceases, the apparatus 35 at the stations return to their normal condition ready for transmission from east to west, the return to the normal condition taking place after a slight interval. Relay R'' is designed to have a necessary hang-over interval which will permit 40 a slow release of its contacts after talking ceases. This hang-over is sufficient to permit all apparatus between both subscribers to return to normal before the contacts of the relay open. During this interval, an audible tone from source G' is 45 sent through the contacts of relay R'' toward the subscriber at station A.

The echo suppressor at B will prevent the tone from being heard by the talker at A until talking from west to east ceases and the echo suppressor relay SE releases and returns to its normal condition. The tone will then be heard by the subscriber at station A during the interval after he has ceased talking and echo suppressor relay SE has released. The tone will continue 55 until relay R'' releases, which occurs when all apparatus in the circuit between the two subscribers has returned to normal. This may be of the order of one-half second, more or less. The echo suppressor relay SE and relay R'' are 60 designed in a manner well known in the art to release their contacts after an interval of time appropriate for use in a particular circuit.

The general principles herein disclosed may be embodied in all types of two-wire and four-wire 65 circuits and are applicable to land lines, submarine cables and radio channels. Although the apparatus at only one terminal has been shown in the drawing the general principles inherent in the apparatus described are applicable to both 70 the other terminal of line L and of submarine cable TC.

What is claimed is:

1. In a system for transmitting message waves between stations, circuit means at one point in the 75

system under control of the message waves transmitted for impressing an audible signal toward the talker at one terminal station, and circuit means at another point in the system for preventing the signal from being heard by the talker except during the interval after he has ceased talking and until the system is in condition under which message waves can be transmitted in the opposite direction and received by the terminal station.

2. In a system for transmitting message waves over a speech transmission channel, a terminal station at one end of the channel, first circuit means for impressing an audible signal toward the talker, and second circuit means for preventing the signal from being heard by the talker except during the interval after he has ceased talking and until the system is in the condition under which message waves can be transmitted in the opposite direction and received by the terminal station, both of said circuit means being located at one end of the speech transmission channel.

3. A two-way message transmission system comprising signaling means for informing the sender how long to wait before a reply can be expected to be received, said signaling means including instrumentalities for transmitting an audible tone toward the sender, said instrumentalities including a source of oscillations of audio frequency, and control means for causing the operation of said instrumentalities during the

entire time the system is in the condition that a reply can not be received.

4. A two-way message transmission system comprising signaling means for informing the sender how long to wait before a reply can be expected to be received, said signaling means including instrumentalities for transmitting a signal toward the sender, control means for causing the operation of said instrumentalities during the entire time that the system is in the condition that a reply can not be received, and circuit means for preventing the signal from reaching the sender except during the interval after he has ceased transmitting his message and until the system is in the condition that a reply can be received.

5. A two-way speech transmission system comprising signaling means for informing the talker how long to wait before an answer can be expected to be received, said signaling means including instrumentalities for transmitting an audible signal toward the talker, control means for causing the operation of said instrumentalities during the entire time the system is in the condition that an answer can not be received, and circuit means for preventing the audible signal from being heard by the talker except during the interval after he has ceased talking and until the system is in the condition that an answer can be received.
